UNITED STATES PATENT OFFICE.

ISIDOR KITSEE, OF PHILADELPHIA, PENNSYLVANIA.

METHOD OF PRODUCING MATRICES.

SPECIFICATION forming part of Letters Patent No. 716,053, dated December 16, 1902.

Application filed February 8, 1902. Serial No. 93,245. (No specimens.)

To all whom it may concern:

Be it known that I, ISIDOR KITSEE, of the city and county of Philadelphia, State of Pennsylvania, have invented certain new and useful Improvements in Methods of Producing Matrices, (Case No. 104,) of which the following is a specification.

My invention relates to an improvement in the method of producing matrices for mani-
10 fold copies, and has more special reference to the method of producing matrices from type-written matters.

The object of my invention is to produce from type-written matters or matters other-
15 wise prepared an efficient and economical matrix adapted to have reproduced therefrom a number of copies of such matters.

In the practice of my invention two steps have to be taken into consideration—first,
20 the production of the copy from which the matrix should be produced; second, the production of the matrix itself. In producing the copy I employ an ink which is indifferent to the fluid used in the production of the ma-
25 trix. This ink should preferably consist of a coloring-matter and a resinous substance dissolved in a hydrocarbon. With this ink the necessary matter is written or printed upon a sheet of material through which the
30 fluid necessary for the production of the matrix can readily be transmitted. This sheet of material, preferably tissue-paper, is then placed face downward on the material de-
signed to become the matrix. This material
35 may consist of any of the well-known metals or may consist of any of the materials used today in the process of lithographing. The gummy and sticky ink of which the char-
40 acters, letters, figures, designs, &c., are formed will adhere to the plate designed to form the matrix, and it is even preferred that with the aid of a roller or otherwise the printed sheet should be carefully pressed against the sur-
45 face of the matrix. In a short time most of the hydrocarbon will be evaporated, especially if the plate is brought in contact with a com-
paratively high temperature. As soon as this state is reached the plate is subjected to the etching-in fluid, and after the necessary depth
50 has been obtained the plate, with its adherent sheet, is first washed off, preferably in water,

and then with a hydrocarbon or other fluid capable of dissolving the resinous ink. The matrix is then ready for use.

It is obvious that different plates may be 55 employed for the etching-in purpose. Different metals require different acids, and if aluminium is employed very diluted hydro-
chloric acid is preferred before others. The different fluids for the different lithographic 60 stones are too well known to need enumeration here. Very diluted sulfuric or acetic acid may be used in conjunction with others.

The underlying principle of my invention, broadly considered, consists therein that 65 sheets transparent for the etching-in liquid should have printed thereon with the aid of ink, opaque to such liquid, the necessary figures, letters, designs, &c., and that these figures, letters, designs, &c., should then be 70 transferred to the plate designed to become the matrix and that then this plate should be subjected to the etching-in fluid, whereby those parts not protected by the ink should be etched in through the etching fluid. Or-
75 dinary printing-presses may then be employed in making manifold copies, which in the case of the original consisting of type-written mat-
ter will have the exact characters of same.

I use the words "resinous substance" in 80 its generic term, including therein also what is known as "gum resins" or "fossil resins."

Wherever in this specification or in the claims following this specification the expression "ink or material opaque to the etch-
85 ing-in fluid" appears, I understand under same "an ink or material capable of with-
standing the corrosive action of said etching-
in fluid," and wherever in this specification or in the claims following this specification the expression "a material transparent to the etching-in fluid" appears I understand under same "a material through which the etching fluid readily passes."

Having now described my invention, what 95 I claim as new, and desire to secure by Letters Patent, is—

1. The method of producing matrices from sheets having written or printed thereon the matter to be reproduced, which consists in 100 printing or otherwise transcribing the matter to be reproduced on a material transparent to

- the etching-in fluid with an ink opaque to said fluid, transferring said matter to the material designed to become the matrix, and then etching in with the aid of suitable fluids that part of said matrix not protected by said ink.
2. The method of reproducing letters, figures, designs, &c., which consists in first producing said letters, figures, designs, &c., on a sheet transparent to the etching-in fluid
- 15 3. The method of producing a matrix for the reproduction of type-written or other matters, which consists in type-writing or otherwise producing the matter to be reproduced with an ink containing a resinous substance in
- 20 solution, covering the surface of the material designed to become the matrix with a sheet having thereon the letters, &c., to be reproduced and etching in that part between said letters not protected by said ink.
- 25 4. The method of producing a matrix for the reproduction of type-written copies which consists in first type-writing the desired matter on a sheet transparent to the etching-in fluid with an ink containing resinous matter
- 30 in solution, then placing said sheet face downward on the surface of the material designed to become the matrix, and finally subjecting said surface to a fluid capable of corroding the parts not protected by the ink, but not capa-

ble of corroding those parts protected by the 35
ink.

5. The method of producing matrices for the reproduction of type-written or other matters, which consists in first producing the matter to be reproduced with an ink impervious to 40 the etching-in fluid on a sheet through which the etching-in fluid is readily transmitted, then placing said sheet face downward on the surface of the material designed to become the matrix, so that the inked-in parts should 45 adhere to said surface, and then subjecting said surface to the etching-in fluid.

6. In the method of reproducing type-written matters the following steps: first, type-writing the desired matter on a sheet transparent to the etching-in fluid with a gummy or sticky ink opaque to said fluid, then placing the type-written copy face downward on the surface of the plate designed to become the matrix, thereby making adherent said 55 copy on said plate through the gummy or sticky ink, then etching in the parts of the plate-surface not protected by said ink, and then printing the desired copies from the matrix so obtained.

In testimony whereof I have hereby signed my name, in the presence of two subscribing witnesses, this 29th day of January, 1902.

ISIDOR KITSEE.
